J. BAMBERGER

LIFTING DEVICE

Filed Nov. 22, 1924

UNITED STATES PATENT OFFICE.

JOSEPH BAMBERGER, OF CINCINNATI, OHIO.

LIFTING DEVICE.

Application filed November 22, 1924. Serial No. 751,419.

My invention relates to lifting devices and has particular reference to the provision of improved means for lifting heavy scenery in theatres, etc.

In the handling of scenery in theatres, it frequently happens that a set is of such weight that it cannot be handled by the available man-power unaided by mechanical means, and it has been the practice in these cases heretofore to send a man up to the rigging lift to attach a "block and fall", that is, pulleys, to the scenery ropes, which arrangement by reason of the mechanical advantage from the pulleys, enables the operators to lift the set.

The principal object of this invention is to provide a device whereby the necessity of employing a man for the attachment of the "block and fall" to the scenery ropes is obviated.

Further objects of the invention will appear from the following detailed description thereof.

In the drawings:

Figure 1 is a perspective of the device attached to the scenery ropes, the latter being shown in diagrammatic arrangement.

Figure 2 is a side elevation of the device.

Figure 3 is a central vertical section of the device.

Figure 4 is a front elevation of the device with parts broken away.

Figure 5 is a top view of the device.

My new lifting device consists of two clamping members, 1 and 2 respectively. The member 1 consists of a back 3 and sides 4—4. The upper portion of the sides 4 are provided with extensions 5 which are perforated to receive a pintle 6. The member 2 comprises a plate 7 having sides 8—8, the said sides being provided at their upper ends with extensions 9 adapted to fit inside the extensions 5 of the sides 4 of member 1. The extensions 9 have registering perforations for the pintle 6. The pintle 6 is arranged to secure the members 1 and 2 together hingedly, and said pintle is removably secured in the assembly by means of a wing nut 10, thereby permitting the ready disassembly of the parts for the purpose herein-after set forth. The member 1 is provided with gripping ribs 11, 12, and 13 respectively. The rib 11 is provided with a number of notches 14, either four or five preferably, said number being determined, however, by the maximum number of the scenery

set ropes with which the device is to be used. The ribs 11, 12 and 13 are of diminishing height, as clearly shown in Figure 3 of the drawings. The member 2 is provided with co-operating gripping ribs 15, 16, and 17, said ribs being arranged on the member 2 to co-operate respectively with the ribs 11, 12 and 13, and the ribs 15, 16, and 17 are, in the order named, of increasing height so as to complement the ribs 11, 12, and 13. The respective pairs of co-operating gripping ribs are off-set, as clearly shown in Figure 3. By reason of the varying height of the several ribs and the arrangement thereof, the free pivotal action of the members about the pintle 6 is provided for. The upper portion of the back 3 of member 1 is provided with an opening 18 located on the vertical axis of the member. The back 3 of member 1 and plate 7 of member 2 are provided with substantially registering openings 19 and 20 also arranged on the vertical axis of the device. The lower portion of the plate 7 of member 2 is provided further with an opening 21 on its vertical axis. All of said openings are provided for the purpose herein-after set forth.

In Figure 1 the ropes 22, 23, 24 and 25 go to the scenic set on the stage which is to be handled. The lower ends of said ropes (at the lower left hand side of the sheet of drawings) are at the point where the operators are located, that is, what is known as the tie floor. Above, the ropes pass over pulleys 26 and individual pulleys 27, 28, 29, and 30, in the rigging loft. When the available man-power is insufficient conveniently to operate the ropes 22, 23, 24, and 25 to lift the scene, the clamping members 1 and 2 are assembled in connection with said ropes, the ropes passing through the notches 14 in the upper rib 11, as shown in Figure 5 of the drawings. The lift rope 31 passing over a pulley 32 in the rigging loft (which rope was heretofore employed for lifting an operator to attach the "block and fall" to the ropes 22, etc.) is secured at its free end in the opening 18 of the member 1. A rope 33 is inserted through the openings 19 and 20 of the clamping members and knotted as shown at 34; said rope is of such dimension as to slide freely through the opening 19. The "block and fall" 35 which is to be raised for the purpose of operating the ropes 22, etc., is secured in the opening 21 of the member 2. So long as the clamping members 1 and 2 are

in open position, as shown in Figure 2 of the drawings, which position they are adapted to attain gravitationally, the ropes 22, etc., are not gripped between the ribs of the members, and the device is thus permitted to slide freely along said ropes. The operator then raises the device by pulling on rope 31, thus raising also the "block and fall" 35. The "block and fall" is thus in position for effective operation by means of the free end of its rope 36. The operator then pulls on the ropes 33 and 36 simultaneously; the pull on rope 33 closes the members 1 and 2 to the position shown in Figure 3, wherein one of the scenery ropes is shown gripped between the ribs, the pull on rope 36 raises the scenic set by pulling down on the lifting device in the usual manner and in accordance with the law of the pulley.

It will be understood that the device above described, while particularly referred to in connection with use in theatres for lifting heavy scenic sets, is also adapted to various other uses, and that modifications within the spirit and scope of the above disclosure and the appended claims may be made in order to adapt the same to such specific duties.

Having thus fully described my invention, what I claim as new and desire to secure by Letters Patent is:

1. A lifting device, comprising a pair of clamping members arranged to be assembled slidably on a rope, means for securing a pulley to said members, means for lifting said members along said rope whereby they are arranged to convey said pulley for the operation of said rope, and means for clamping said members upon said rope.
2. A lifting device, comprising a pair of clamping members, means for hingedly assembling said members slidably upon a rope, means for securing a pulley to said members, means for lifting said members along said rope whereby they are arranged to convey said pulley for operation of said rope,

and means for clamping said members upon said rope.

3. A lifting device comprising a pair of clamping members, means for hingedly assembling said members slidably upon a rope, means whereby said device is arranged to convey pulleys for the operation of said rope, a rope arranged to engage the free end of one of said members through an opening in the other member whereby said members may be clamped upon said first rope, and ribs on said members arranged to grip said first rope when said members are closed.

4. A lifting device comprising a pair of clamping members, each of said members being provided with gripping ribs, the upper rib of one of said members being provided with notches to provide passage for ropes, means for hingedly securing said members together upon said ropes, said members being arranged to be maintained gravitationally in open position, means for raising said members when in open position along said ropes, whereby said device is arranged to lift pulleys for the operation of said ropes, and means arranged to clamp said ribs upon said ropes.

5. A lifting device comprising a pair of clamping members, each of said members being provided with gripping ribs, the upper rib of one of said members being provided with notches to provide passage for ropes, means for hingedly securing said members together upon said ropes, said members being arranged to be maintained gravitationally in open position, means for raising said members when in open position along said ropes, whereby said device is arranged to lift pulleys for the operation of said ropes, and a rope arranged to engage the free end of one of said members through an opening in the other member, whereby a pull upon said rope is arranged to clamp said members upon said first mentioned ropes.

JOSEPH BAMBERGER.
